UNITED STATES PATENT OFFICE.

BRYSON D. HORTON, OF DETROIT, MICHIGAN.

ELECTRICAL SWITCH.

1,190,903.

Specification of Letters Patent. Patented July 11, 1916.

Application filed November 18, 1913. Serial No. 801,755.

To all whom it may concern:

Be it known that I, BRYSON D. HORTON, a citizen of the United States, residing at Detroit, in the county of Wayne and State of Michigan, have invented certain new and useful Improvements in Electrical Switches, of which the following, taken in connection with the accompanying sheet of drawings, is a full, clear, and concise description.

10 My present invention relates to certain improvements in electrical switches, and more particularly to switch operating means especially applicable to switches of the inclosed type in which the switch mechanism is arranged within and protected by a suitable housing. In switches of this character it is necessary to provide means for operating the switch from the outside of the casing without opening the casing, as the 15 protective advantages of the latter would not otherwise be secured. These operating means should, however, be of as simple a character as possible in order to secure sureness of action and reduce the cost of manufacture. The operating means should also be preferably of such a nature as to permit easy access to the interior of the casing by opening the cover so as to permit inspection or repair of the switch, replacement of the 20 fuses, or other adjustments.

One of the objects of my invention is to provide a switch construction including an operating means of a very simple character capable of operating the switch from the 25 outside of the casing and of such a nature as to permit the opening of the cover of the casing without dismantling the operating means. It is also desirable that the operating mechanism be such as to produce a substantial throw of the movable switch contacts so as to avoid arcing and to provide 30 for a quick break. For the latter purpose it is often desirable to employ an accelerating spring, and, by affording a substantial movement of the movable contacts, provision may be made for a considerable tensioning of such accelerating spring. This increased tension enables the spring to act more effectively in producing the quick break.

40 It is another object of my invention, therefore, to provide a switch operating mechanism of such character and so related to the parts of the switch as to be capable of producing a substantial movement of the movable contacts of the switch, to produce a quick break, and to make possible the effi-

cient use of an accelerating spring where such spring is considered desirable. It is a further object of the invention to provide an improved accelerating spring mechanism. 60

In switches of the knife-blade type and in similar constructions in which blades are received between the jaws of fixed contacts, a substantial force is required to be exerted upon the movable contacts in order to open 65 the switch. This force should be applied in such a way as to separate all of the contacts simultaneously so as to break both sides of the line at the same instant. Moreover it is desirable to apply the force in such 70 manner as not to twist or distort the parts of the switch, or apply undue stresses to the elements thereof. For example, if the switch be of the knife-blade type having two or more blades or movable contacts connected 75 by a bar or cross-head, it is desirable to apply the opening force in such manner as to move all of the blades or movable contacts simultaneously and evenly so as to break all of the contacts at the same time and not to 80 twist the knife-blades about their pivots, or rack the connections between the blades and the cross heads.

It is an object of my invention to avoid these objectionable possibilities. This I accomplish by providing operating means adapted to exert a substantially balanced force upon the movable contacts with respect to their points of support. 85

More specifically, it is an object of my 90 invention to provide an operating means connected to the cross-head of the knife-blade or similar switch in such a way as to exert a balanced force thereon as, for instance, by connecting the operating means 95 to an intermediate portion of the cross-head between the points of connection of the movable contacts thereto. In this way satisfactory operation of the switch is insured, and, at the same time, a simple and cheap 100 construction may be employed, accurate alignment and fitting of the parts, and rigidity thereof not being required.

Other objects and advantages of the invention will appear from the following description of one preferred embodiment thereof, which is shown in the accompanying drawings and described in detail as illustrative of a preferred application of the principles of the invention. 105

In the drawings:—Figure 1, illustrates a plan view of an armor-clad switch incor-

porating the features of my invention, a fragment of the cover being shown in its open position. Fig. 2 is a view in side elevation showing the operating crank in 5 the position it assumes when the contacts are closed. Fig. 3 is a cross sectional view taken on line A A of Fig. 1, showing the portion of the operating handle and the contacts in the position assumed when the 10 latter are in their open position.

Referring now in detail, 1 indicates a metallic casing provided with a hinged cover 2. Upon the bottom of the casing is mounted 15 a base of insulating material 3 upon which the jaw contacts 4 and co-operating pivotal knife-blade contacts 5 are mounted. The knife-blade contacts 5 are connected by means of a cross head 6, which cross head carries an eye 7 which forms a bearing for the end 8 of the operating U shaped crank 9 the latter being mounted in a suitable bearing 10 in the side of the casing.

The operating crank is thus supported laterally of the pivotal supports of the knife 25 blades and is preferably so arranged with relation to the latter as to be capable of producing a substantial throw of the switch. This is best accomplished by locating the 30 crank bearing in substantial alinement with the pivotal bearings of the knife blades, or in such relation thereto as to permit of a large range of movement of the knife blades and operating crank together. Preferably 35 also the cross head connecting the knife blade contacts is arranged at or near the ends of the latter as this gives better support to the blades and maintains them in more satisfactory alinement, and the inner arm of the operating crank is extended into 40 proximity with and connected to the cross head.

In the construction illustrated the interior arm 9^a of the operating member extends in a direction substantially parallel with and adjacent to the side of the casing where it is 45 out of the way, and it carries a transverse extension portion 9^b which extends substantially parallel with the cross-head. Connection is made between this lateral extension 50 portion and the cross-head in such a way as to provide for a balanced pull upon the latter, this being accomplished in the construction shown by passing the lateral extension portion through the eye 7, as heretofore described. The eye 7 being located at or near 55 the center of the cross-head, results in a balanced force being exerted upon the latter by the operating crank and the connection being of a loose or pivotal nature permits the 60 force to be equalized so that irregularities in the movement of the operating crank, such as might be caused by improper alinement thereof, will not be transmitted to the cross-head. In the particular construction of the 65 switch illustrated the exterior arm 9^c of the

operating crank extends substantially parallel with the side of the casing, thus producing a compact structure, and it is also preferably of greater length than the interior arm of the crank so affording increased 70 leverage to facilitate the operation of the switch by the handle 11 provided at the end of the crank.

By oscillating the crank 9, an electrical circuit may be established or broken as desired, the "on" position of the switch mechanism being shown in Fig. 1 while the "off" position is shown in Fig. 3 of the drawings. In order to insure a positive "on" connection between the movable and stationary contacts, I provide an expansion spring 12, one end of which is held by means of a hook 13, fast-to the side of the casing; the opposite end of the spring is connected to the operating crank 9 by means of a pivoted two part 80 lever connection consisting of links 14 and 15 pivoted together at 16. The links 14 and 15 are curved links, as shown more clearly in Fig. 3, so as to obtain the greatest possible leverage in the available space within 85 the receptacle. The link 15 is carried by the arm of the U-shaped crank 9, the connection being by means of a formed sleeve 17 integral with said link and surrounding the crank operating arm 9^c. The hook 13 which 90 holds one end of the spring is so positioned with respect to the pivot point of the oscillating crank arm as to cause the spring to expand when the contacts are thrown into their "on" position, the spring tension opposing this movement, the tendency being to 95 open the switch. This tendency is overcome as soon as the knife-blades fully pass between the jaw contacts into full contact-making position. This movement causes the 100 spring to oscillate during its expansion so that its point of connection with the hook 13, its point of connection with link 14, the pivot point 16 of the links 14 and 15 and the pivot point of the operating member in the 105 side of the casing are substantially on a dead center line. Thus the spring pressure is 110 prevented from being exerted to move the blade contacts one way or another excepting to assure their positive disconnection with the jaw contacts when being thrown to "off" position. However, as soon as the operating handle is moved to break the connection between the contacts and the pivoted connections 16 of the links 14 and 15 is lowered and moved 115 out from this alinement, the tension is immediately directed to contract the spring 120 the latter exerting a corresponding tendency to throw the movable switch contacts to their "off" position.

The considerable degree of movement of the movable contacts for which the preferred construction of my switch provides permits of a substantial tensioning of the accelerating spring when the switch is manipulated 120

and insures the effective operation of such a spring. The appreciable movement of the crank or operating handle provided for also enables the operating handle to assume widely separated positions which indicate clearly at all times the condition of the switch whether closed or open. The large range of movement of the parts is also advantageous in case it is desired to provide means for locking the switch in open position as it permits the contacts to be widely separated before locking and may in fact be used to provide three positions for the switch, namely: a closed position, an operative open position and a locked open position, as disclosed, for instance, in my companion Patent, No. 1,114,988.

I have shown and described but one specific embodiment of my invention, but I do not wish to be understood as limiting myself to structural details for the specific arrangement of parts, as these may be changed and varied without departing from the spirit and scope of my invention as above indicated, and as set forth in the following claims.

Having thus described my invention what I claim as new herein and desire to secure by Letters Patent is:—

1. A switch of the character described, including a metallic casing provided with a cover, a switch mechanism therein, said switch mechanism including a pair of spaced-apart stationary jaw contacts, a pair of pivoted movable knife blade contacts, a cross-head of non-conducting material connecting said knife blade contacts at their free ends, an operating crank journaled in said casing laterally of and substantially in line with the axis of the movable pivoted knife blade contacts, said operating crank arm having portion extending adjacent to said cross-head at a point intermediate its connection with the movably mounted pivoted knife blade contacts and operably connected thereto, and means for accelerating the movement of the movable pivoted knife blade contacts when being thrown to their "off" position, said means comprising an expansion spring connected at one end to one side of the casing, and at its opposite end to the operating crank arm, substantially as described.

2. In an iron-clad switch of the character described, in combination with stationary and movable contacts, an operating crank co-operating with said contacts and extending through the casing and providing for exterior manipulation, an expansion spring connected at one end to the side of the casing and at its opposite end to a link, a second link having pivot connection with said first link, the points of connection of said spring and operating links being such with respect to the bearing point of the operating crank that these points

will be brought substantially into alignment on a dead center line with the spring fully expanded by the movement of the operating crank when connection is made between the contacts.

3. In a switch of the character described, the combination of a metallic casing, a switch mechanism therein, said switch mechanism including pairs of spaced-apart co-operating contacts, one pair being mounted stationary upon a base of insulating material, and the other pair being movably mounted with respect thereto, of a cross-head made of insulating material connecting the movable contacts at their free ends, and a one-piece operating crank mounted in the side of the casing, its inwardly-extending free end having operable connection with the insulating cross-head at a point intermediate the contacts and provided with an exterior end-portion, said crank being pivotally mounted in the side of the casing at a point substantially in line with the pivot points of the movable contacts, whereby substantial movement of the movable contacts through an arc of a circle is obtained when operated.

4. A switch mechanism including a plurality of spaced stationary contacts, a plurality of spaced knife-blade contacts pivotally mounted in co-operative relation thereto, a cross-head connecting said spaced knife-blade contacts near their free ends, an operating member pivotally supported laterally of and in substantial alignment with the pivot points of said knife-blade contacts, and provided with a portion extending into proximity to and operably connected with the cross-head by means exerting a substantially balanced force on said cross-head with relation to the pivot supports of said knife-blade contacts when said operating member is operated to actuate the switch.

5. A switch mechanism including a plurality of spaced stationary contacts, a plurality of spaced knife-blade contacts pivotally mounted in co-operating relation thereto, a cross-head connecting said spaced knife-blade contacts near their free ends, an operating member pivotally mounted laterally of and in substantial alignment with the pivot points of said knife blade contacts and having a portion extending from the pivotal support into proximity to said cross head, and means connecting said portion with said cross-head, intermediate of the knife-blade contacts, whereby said member will exert a substantially balanced force upon said cross-head.

6. A switch mechanism including a plurality of spaced stationary contacts, a plurality of spaced knife-blade contacts pivotally mounted in co-operative relation thereto, a cross-head connecting said spaced

- knife-blade contacts near their free ends, an operating crank member pivotally supported substantially in alinement with the pivot points of the knife blade contacts and including an arm extending toward the cross-head, and a transverse member carried by said arm extending adjacent to said cross-head and connected therewith by means applying a substantially balanced force to said cross-head when said crank is operated to open or close the switch.
7. A switch mechanism including a pair of spaced stationary contacts, a pair of spaced pivotally mounted knife-blade contacts, a cross-head connecting said knife-blade contacts near their free ends, an operating crank member supported and journaled at a point substantially in alinement with the pivot points of the knife-blade contacts and comprising an arm extending toward the cross-head, said arm terminating in a portion substantially parallel to the cross-head and being operably connected therewith at a point substantially midway between the spaced knife-blade contacts, whereby substantial movement may be imparted to the knife blade contacts when moved toward or away from the stationary contacts, and a substantially balanced force is applied to said cross-head.
8. A switch mechanism including a plurality of spaced stationary contacts, a plurality of spaced pivotally mounted knife-blade contacts, a cross-head connecting said knife-blade contacts near their free ends, an operating member pivotally supported substantially in alinement with the pivot points of said knife-blade contacts and provided with a portion extending into proximity to said cross-head, and means loosely connecting said portion with the central portion of said cross-head whereby said operating member will exert a substantially balanced force on said cross-head.
9. A switch mechanism including a plurality of spaced stationary contacts, a plurality of spaced pivotally mounted knife blade contacts, a cross head connecting said knife blade contacts near their free ends, an operating member pivotally supported laterally of the pivot points of said knife blade contacts and provided with a portion extending into proximity to said cross head, and means connected to an intermediate portion of said cross head and forming an eye through which said operating member extends.
10. A switch of the character described, including a casing, a base of insulated material therein, a plurality of spaced stationary contacts mounted on said base, a plurality of spaced knife-blade contacts pivotally supported at one end on said base and adapted when extending in a direction substantially parallel to said base to engage said station- ary contacts, a cross-head of insulating material connecting said knife-blade contacts near their extremities, an operating member having pivotal support laterally of and in substantial alinement with the pivotal points of said knife blade contacts and including an actuating handle outside of said casing, and a member inside of said casing, said member having a portion extending toward said cross-head and a portion extending substantially parallel therewith operably connected thereto.
11. A switch of the character described, including a casing provided with a cover, a switch mechanism within the casing including a plurality of spaced stationary contacts and a plurality of spaced coöperating pivoted knife blade contacts, a cross-head of insulating material connecting the knife-blade contacts at their free ends, an operating crank journaled in the side of the casing at a point substantially in line with the pivot points of the knife-blade contacts, said operating crank being provided with a pair of arms, one arm being located within the casing, and provided with a lateral extension having operable connection with the cross-head at a point intermediate the spaced knife-blade contacts, the other arm being longer and arranged exterior of the casing and serving as an operating member by means of which the circuit may be controlled.
12. A switch of the character described, including a metallic housing provided with a cover, said switch mechanism including a pair of spaced stationary contacts and a pair of spaced coöperating pivoted contacts, a cross-head connecting the extremities of said movable contacts, an operating crank journaled in the housing and adapted for exterior manipulation, said operating crank provided with arms which are substantially parallel with the sides of the casing and having a bearing in the side of the casing substantially in alinement with the pivot points of the movable contacts, one arm being interior of the casing and provided with an extension which connects with the cross-head, whereby the movable contacts may be caused to transcribe a substantial arc when moved toward or away from the stationary contacts, and means for accelerating the movement of the knife-blade contacts when being thrown to their "off" position, said means comprising a spring one end of which is connected to the casing and the other end of which is connected to the operating crank.
13. A switch of the character described, including a casing provided with a hinged cover, switch mechanism within the casing including stationary and coöperating pivoted contacts, a cross-head connecting the movable contacts at their free ends, an operating crank journaled in the side of the casing at a point substantially in line with the pivot

points of the movable contacts, said operating crank being provided with interior and exterior arms, the arm within the casing extending toward the cross-head and being provided with a lateral extension in a plane parallel with the cross-head, and a connecting link between the operating crank and the cross-head, and means for accelerating the movement of the knife-blade contacts when being thrown to their "off" position, said means comprising a spring one end of which is connected to the casing and the other end of which is connected to the operating crank.

14. A switch of the character described, including a casing having a bottom, substantially vertical side walls and a hinged cover, a base of insulating material mounted upon the bottom of said casing, a plurality of stationary jaw contacts on said base, a plurality of knife-blade contacts pivotally mounted at one end on said base and adapted to co-operate with said stationary jaw contacts, an insulating cross-head connecting said knife-blade contacts near their free ends, a lever pivoted in a vertical wall of said casing and having a portion extending in proximity to and pivotally connected with an intermediate portion of said cross-head, said lever having an operating handle outside of said casing, whereby said lever may be operated to exert a balanced force on said cross-head to open said switch, and said cover may be

opened without dismantling said switch operating mechanism.

15. A switch of the character described, including a casing having a bottom, substantially vertical side walls and a hinged cover, a base of insulating material mounted upon the bottom of said casing, a plurality of stationary jaw contacts on said base, a plurality of knife-blade contacts pivotally mounted at one end on said base and adapted to co-operate with said stationary jaw contacts, a cross-head of insulating material connected to the outer ends of said knife-blade contacts, an eye affixed centrally to said cross-head, a lever pivotally mounted in a vertical wall of said casing and having a portion passing through said eye and having a handle portion outside of said casing, whereby said lever will exert a substantially balanced force on said cross-head to open said switch and said cover may be opened without dismantling the switch-operating mechanism, and an accelerating spring for assisting in the operation of said switch.

In witness whereof I have hereunto set my hand in the presence of two subscribing witnesses,

BRYSON D. HORTON.
